UNITED STATES PATENT OFFICE.

LUKE D. REED, OF BURNHAM, ILLINOIS.

FLYING-BOAT.

1,398,467.

Specification of Letters Patent. Patented Nov. 29, 1921.

Application filed October 4, 1919. Serial No. 328,446.

To all whom it may concern:

Be it known that I, LUKE D. REED, a citizen of the United States, residing at Burnham, in the county of Cook and State 5 of Illinois, have invented certain new and useful Improvements in Flying-Boats, of which the following is a specification, reference being had to the accompanying drawings.

10 This invention relates to flying machines of the heavier than air type, and particularly to hydro-aeroplanes or flying boats.

The general object of my invention is to provide a flying machine of this type which 15 will have a greater stability than ordinary flying machines in which the planes have a greater sustaining capacity, and in which the control is simpler, more direct, and more effective than on ordinary aeroplanes.

20 A further object is to provide a flying boat in which the aerofoils extend longitudinally of the boat instead of projecting laterally therefrom, thus making the flying machine more compact and permitting them 25 to be more thoroughly braced and supported against strain than is possible where the planes extend laterally outward.

A further object is to provide a flying machine of this character which may be 30 more easily landed than with the ordinary flying boat, and which may be reversed.

Other objects will appear in the course of the following description.

My invention is illustrated in the accompanying drawings, wherein:—

Figure 1 is a side elevation of a flying machine constructed in accordance with my invention;

Figure 2 is a front elevation thereof;

40 Figure 3 is a section on the line 3—3 of Fig. 1;

Figure 4 is a fragmentary top plan view, partly broken away, of the rear end of the machine.

45 Referring to the drawings, 10 designates the hull of the boat, which may be of any suitable stream-line form and have any desired dimensions, and which may be fitted, as regards its interior, in any suitable man-

50 ner. I have shown a tractor propeller 11 at the forward end of the boat and a steering rudder 12 at the rear end of the boat. I have also shown landing wheels 13 operatively supported upon the hull of the boat

55 adjacent the forward end thereof and a tail skid 14 at the rear end of the hull. All of

these parts may be of any suitable construction or arrangement, and I do not wish to be limited to the particular details of these parts illustrated.

60 The body of the boat is formed preferably with a plurality of planes or aerofoils, shown as three in number, and designated 15, 16 and 17. The plane 15 is disposed above the top of the hull and has a length

65 nearly that of the hull itself and extends continuously across above the hull. The planes 16 and 17 each extend laterally from the hull itself, the plane 16 being disposed slightly above the upper surface of the hull.

70 These planes 16 and 17 also extend nearly the full length of the hull and the full length of the plane 15. These planes 15, 16 and 17 are braced from each other by the outer struts 18 and the plane 15 is support-

75 ed adjacent its middle by the struts 19 which extend upward from the hull. Flying wires, incidence wires, and the usual drift wires connect the several planes to the hull in the usual manner. The particular position of

80 these drift and incidence wires form no part of my invention. These wires will, of course, extend from the extremities of the struts to the hull and to adjacent struts and will cross each other in the usual manner. I

85 do not wish to be limited to any particular construction of the planes or aerofoils nor to any particular construction for the struts, nor do I wish to be limited to the disposition

85 of the planes one immediately above the other in alinement, as the uppermost plane or aerofoil might be disposed in advance of the lower planes or vice versa.

90 Disposed between the planes or aerofoils 16 and 17 are the elevating and stabilizing planes corresponding to the ailerons found on ordinary aeroplanes, and designated 20.

95 These controlling planes are relatively long, though shorter than the planes 16 and 17, and are pivotally mounted at their middles, 100

as at 21, on shafts extending into the hull of the boat. These shafts are connected to suitable controlling mechanism disposed within the boat whereby the inclination of

105 these planes 20 may be changed. Preferably, the shaft 21 will be operatively connected to controlling levers 22 operating over suitable toothed racks 23. The rudder

110 12 may be controlled by operating wires 24, in turn connected to suitable controlling levers 25 disposed within the hull of the boat and operating over racks 26.

I do not wish to be limited to the use of a forward tractor propeller, as the propeller might be located at the rear end of the boat or the boat might be provided with two propellers, one at its rearward end and one at its forward end, and reversing mechanism might be provided for reversing the rotation of the propellers to cause the boat to travel in either direction.

10 The advantages of my construction are due to the fact that while the planes have a relatively great area, they do not project laterally of the boat to as great an extent as in the ordinary air plane but extend longitudinally of the boat. This eliminates the strains to which the usual aerofoils are subjected and permits of a lighter and stronger construction of the aerofoils and the bracing connections. The uppermost 15 plane 15 is the balance plane. The air passing between the several planes 15, 16 and 17 hugs the boat, giving the planes more resistance and a greater load capacity. It will be noted that the wings or ailerons 20 or control planes, when they are shifted to carry the forward ends of the planes 20 upward causes the air to exert a lifting force upon the forward end of the machine and causing this air to be forced downward 25 against the rear end of the planes 17, thus turning the nose of the machine upward and at the same time exerting a downward force 30 on the tail of the machine. Vice versa, when the controlling planes 20 are turned 35 with their forward end upward, the air is forced upward against the rear portions of the planes 16 and the air exerts a downward pressure upon the forward portions of the controlling planes 20, thus causing 40 the boat to dive. Of course, the two controlling planes are operated independently 45 of each other so that the machine may be banked on turns. The planes are so spaced that the machine will not turn over or fly upside down.

A flying boat constructed in accordance with my invention will be particularly steady, may be readily and directly controlled, and by reversing the engine, a relatively slow landing will be made. Of course, the planes will be given suitable camber and will have a suitable incidence angle. The planes are illustrated diagrammatically.

I claim:—

55 1. A flying machine comprising a body having a propeller at one end, a balance plane disposed above the body and operatively connected thereto and extending approximately the full length of the body, a plurality of planes disposed below the balance plane and extending laterally from the body, all of said planes having a length

parallel to the axis of the body greater than the width of the planes transverse to the axis, and elevating planes extending longitudinally parallel to the axis of the body and disposed between a pair of main planes and having a length greater than the distance between the adjacent planes but less in length than the length of said planes, and means for controlling the position of said elevating planes.

2. A flying machine of the character described having a boat-shaped body, a propeller at one end of the body, a balancing plane disposed above and extending across the body and extending longitudinally nearly the whole length of the body, said plane having a greater dimension from front to rear than laterally, a plurality of planes extending laterally from the body and disposed in spaced relation and having a length nearly equal to the length of the body and a width less than their length, struts bracing the planes from each other, and a pair of controlling planes pivotally mounted between a pair of the planes extending from the body and having a length greater than the distance between said adjacent planes but less than the length of said planes, said controlling planes extending equally on each side of the pivotal axis, and means for turning the controlling planes to change their angle of inclination.

3. In a flying machine, a body, upper and lower planes mounted upon the body and having a length parallel to the body greater than the width of said planes at right angles to the body, and elevating planes disposed, one on each side of the body and between said first named planes, said elevating planes being pivotally mounted midway of the length of the first named planes and having a length greater than the distance between said first named planes but less than the length of the first named planes.

4. A flying machine of the character described having a boat-shaped body, planes extending laterally from the hull of the boat-shaped body adjacent the upper face thereof, planes extending laterally from the boat-shaped body below the first named plane, a balancing plane disposed above the boat-shaped body, all of said planes having a length parallel to the body greater than the width at right angles to the body, a propeller mounted upon the body, and elevating planes disposed between each pair of first named planes and on each side of the boat-shaped body.

In testimony whereof I hereunto affix my signature.

LUKE B. REED.
